UNITED STATES PATENT OFFICE

99,676

DESIGN FOR A GLASS GOBLET

David King Irwin, Short Hills, N. J., assignor to Morgantown Glass Works, Morgantown, W.
Va., a corporation of West Virginia

Application March 12, 1936, Serial No. 61,588

Term of patent 7 years

To all whom it may concern:

Be it known that I, David King Irwin, a citizen of the United States, residing at Short Hills, Essex County, New Jersey, have invented a new, original, and ornamental Design for a Glass Goblet, of which the following is a specification, reference being had to the accompanying drawing forming part thereof, in which the single figure is a view in perspective of the goblet showing my new design.

I claim:

The ornamental design of a glass goblet, as shown.

D. KING IRWIN.
